HUGH P. FELL, OF NEW YORK, N. Y.

ICE-FREEZING TANK.

Application filed July 29, 1926. Serial No. 125,766.

The present invention is concerned with the provision of a freezing tank which may have a wide range of utility in the refrigeration art and which finds its preferred embodiment in a tank for freezing ice.

Until a fairly recent date the common practice in ice freezing tanks was to use separate ice cans arranged in rows with the long refrigerating coils running lengthwise 10 of the tank between the rows of cans. This arrangement had three outstanding disadvantages. In the first place the refrigerating coils were frequently broken by striking the ice cans against them as they were lowered into place. In the second place it was necessary to drain off all of the brine in the tank when repairing a leaky coil. In the third place the long horizontal ammonia coils could not be kept flooded due to the 20 fact that the mixture of gasified and liquid ammonia needed to travel a long distance before the gas could separate out. This last disadvantage, of course, resulted in inefficient refrigeration.

Recently this practice has been somewhat modified and the use of batteries or groups of ice cans has become general. The longitudinal rows of ammonia coils between the cans have been eliminated and the coils are 30 put in a separate compartment either under the cans or beside them. In this manner the danger of breaking the ammonia coils has been lessened, but the freezing tanks are still highly inefficient due to the fact that the 35 coils are unduly long and due to the fact that the difficulty of repairing a coil has been increased rather than lessened by placing the coils in compartments.

In accordance with the present invention 40 I have provided a freezing tank which eliminates all of the above noted disadvantages. Short lengths of coils connected to one or more headers are utilized, these coils preferably extending transversely of an elongated compartment in the tank. The connection of the coils with the header or headers is such that a damaged coil may be readily uncoupled and removed without draining any brine from the tank. The removal 45 of the ice cans will lower the level of the brine sufficiently to provide access to the coil couplings. The relatively short length coils also provide for much more rapid and efficient refrigeration since the partially

gasified refrigerant is not trapped in a long 55 run of the coil. Any coil of the series may be cut out or removed for repairs without materially affecting the efficiency of the system.

Objects of the invention are to provide a 60 tank of the general character outlined above which will be of simple, practical construction, well suited to the requirements of economical manufacture, and well suited for use in the conversion of an old type tank 65 into a tank embodying the invention. With the above noted and other objects in view the invention consists in certain novel features of construction and combinations and arrangements of parts as will be more fully 70 hereinafter described and set forth in the claims.

The invention may be more fully understood by reference to the accompanying 75 drawings, wherein,

Fig. 1 is a broken top plan view of my improved ice freezing tank, part of the coil compartment cover being broken away for the sake of clearness;

Fig. 2 is a longitudinal sectional view on 80 the line 2-2 of Fig. 1;

Fig. 3 is a transverse sectional detail on the line 3-3 of Fig. 2;

Fig. 4 is a fragmentary plan view of one end of the coil compartment with the cover 85 removed;

Fig. 5 is a sectional detail through the bottom of the accumulator; and

Fig. 6 is a sectional detail of one of the headers showing perforated baffle plates. 90

In the drawings I have used the reference character 10 to designate a brine tank divided by a pair of parallel longitudinally extending vertical partitions 11 into a central coil compartment 12 which runs substantially the full length of the tank and which communicates at its ends with the ice can compartments 13 at each side of the tank. Batteries of ice cans 14 are shown in the ice can compartments. Agitators may be 100 provided in both ends of the coil compartment 12 for maintaining a continuous brine circulation through the coil compartment. For purpose of illustration, however, I have shown only one agitator 14' mounted near 105 the end of compartment 12 adjacent the ammonia accumulator 15.

The means for withdrawing the vapors

from the headers, condensing it and returning it to the accumulator, forms no part of the present invention, and in order to simplify the drawings I have shown no mechanism for accomplishing this purpose.

A pair of headers 16 and 17 each communicate with the accumulator 15 at one end and are connected together at their opposite ends by a coupling 18. These headers are 10 preferably spaced apart the full width of the chamber 12 and to each header there are connected a series of short transversely disposed refrigerating coils designated generally by the reference numeral 19. As best 15 seen in Fig. 3 each of the coils 19 includes a vertical leg 20 connected by a coupling 21 to the bottom of one of the headers 16, 17. Liquid ammonia flows from the header down the vertical leg 20, then upwardly through 20 a tortuous course defined by a connected series of horizontal pipes 22, the return to the header being through a pipe 23 communicating with the top of the header and connected thereto by a coupling 24. If de- 25 sired the headers may be horizontally divided by apertured plates 25 separating the liquid ammonia in the bottom of the headers from the ammonia gas in the top.

It will be noted in Fig. 3 that the horizontal pipes 22 of one coil 19 are staggered 30 relatively to the horizontal pipes of a laterally adjacent coil so that the pipes themselves constitute baffles for the brine in its flow through the compartment 12. Obviously 35 any desired number of additional baffles 40 depending from the cover 30 of compartment 12 may be utilized.

As illustrated the coils 19 are connected alternately to opposite headers 16 and 17. 40 It is to be understood however that only one header might be used instead of two and that instead of using a central coil compartment 12, I might use any desired number of compartments. For example, two compartments, one located at each side of the freezing tank might be utilized. In any event the coil compartments should be relatively elongated and the refrigerating coils would be disposed transversely thereof, and each 50 consist of a relatively small, readily removable unit.

From the foregoing description it will be seen that when any one of the coils 19 is out of order, it may be readily removed and repaired by simply removing cover 30 of the coil compartment and enough of the ice cans to lower the brine level to a point below cou-

pling 21. The couplings 24 and 21 of the particular coil 19 which has been removed can be blocked up and the system continue 60 to function in the absence of the coil. The refrigerating capacity will be only slightly reduced when a coil is removed because of the short length of the pipe coil unit. The pipe coils will be more nearly 100% flooded 65 because of the fact that the coils are short and there will be little gas trapped in them. The distance which the ammonia travels in a horizontal direction relatively to the head of ammonia is considerably reduced, and the 70 circulation in consequence is more rapid and efficient giving a rate of heat transfer which will result in the production of a greater tonnage of ice with a smaller total footage of pipe coils.

Obviously various changes and alterations might be made in the general form and arrangement of the parts described without departing from the invention.

I claim:

1. An evaporator for cooling brine tanks or the like including a pair of parallel longitudinally extending refrigerant headers, relatively short transversely disposed refrigerating coils, the ends of alternate coils 85 communicating with the opposite headers, and couplings for the coils arranged closely adjacent the headers to facilitate the removal of a single coil.

2. An evaporator for cooling brine tanks 90 or the like including a pair of parallel longitudinally extending refrigerant headers, relatively short transversely disposed refrigerating coils, the ends of alternate coils communicating with the opposite headers, and couplings for the coils arranged closely adjacent the headers to facilitate the removal of a single coil, said coils extending transversely of the longitudinal axes of the headers and being disposed in the space between 100 the headers.

3. An evaporator for cooling brine tanks or the like including a pair of parallel longitudinally extending refrigerant headers, relatively short transversely disposed refrigerating coils, the ends of alternate coils 105 communicating with the opposite headers, and couplings for the coils arranged closely adjacent the headers to facilitate the removal of a single coil, the horizontal runs of adjacent coils being staggered to serve as baffles for a circulating brine tank to be cooled.

HUGH P. FELL.
